CLAIM

The ornamental design for a hand tool attachment, as shown and described.

DESCRIPTION

FIG. 1 is a top perspective view of an assembled hand tool attachment of the present invention;

FIG. 2 is a bottom perspective view of an assembled hand tool attachment of the present invention;

FIG. 3 is an exploded top perspective view of an assembled hand tool attachment of the present invention;

FIG. 4 is a first side view perspective view of an assembled hand tool attachment of the present invention;

FIG. 5 is a second side view perspective view of an assembled hand tool attachment of the present invention;

FIG. 6 is a third side view of an assembled hand tool attachment of the present invention;

FIG. 7 is a fourth side view of an assembled hand tool attachment of the present invention;

FIG. 8 is a bottom view perspective view of an assembled hand tool attachment of the present invention; and,

FIG. 9 is a top view perspective view of an assembled hand tool attachment of the present invention.

The broken lines form no part of the claimed design.
